(57) **CLAIM**

The ornamental design for a hair styling and drying device, as shown and described.

DESCRIPTION

FIG. 1 is a perspective view of the claimed design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a perspective view of the claimed design, wherein the brush head component is shown detached and separately for clarity of illustration;

FIG. 9 is a front elevational view thereof, wherein the brush head component is shown detached and separately for clarity of illustration;

FIG. 10 is a rear elevational view thereof, wherein the brush head component is shown detached and separately for clarity of illustration;

FIG. 11 is a right side elevation view thereof, wherein the brush head component is shown detached and separately for clarity of illustration;

FIG. 12 is a left side elevation view thereof, wherein the brush head component is shown detached and separately for clarity of illustration;

FIG. 13 is a top plan view thereof, wherein the brush head component is shown detached and separately for clarity of illustration; and,

FIG. 14 is a bottom plan view thereof, wherein the brush head component is shown detached and separately for clarity of illustration.

The broken lines in the drawing figures illustrate environmental structure and form no part of the claimed design.

1 Claim, 10 Drawing Sheets
